[57] CLAIM

The ornamental design for a diagnostic aid for determining a degree to which a person's life is in balance, as shown and described.

DESCRIPTION

FIG. 1 is a perspective view of a diagnostic aid for determining a degree to which a person's life is in balance, showing my new design, the broken line showing is for illustrative purposes only and forms no part of the claimed design;

FIG. 2 is a top plan view thereof;

FIG. 3 is a side elevational view thereof; the opposite side elevational view being identical thereto;

FIG. 4 is a bottom plan view thereof; and,

FIG. 5 is an end elevational view thereof; the opposite end elevational view being identical thereto.
